CLAIM

The ornamental design for a pillow, as shown and described.

DESCRIPTION

FIG. 1 is a top, front, and left side perspective view of a pillow showing my new design;

FIG. 2 is a front elevational view thereof;

FIG. 3 is a rear elevational view thereof;

FIG. 4 is a left side elevational view thereof, the right side being a mirror image of that shown;

FIG. 5 is a top plan view thereof; and

FIG. 6 is a bottom plan view thereof.

The cross-hatch surface shading employed is understood to indicate conventional fabric and is further understood to repeat uniformly across the surfaces represented.

FIG. 2.

FIG.3.
